US0D1010067S

(12) **United States Design Patent** (10) **Patent No.:** **US D1,010,067 S**
(45) **Date of Patent:** **** Jan. 2, 2024**

(54) **HEATED LID FOR PORTABLE BATTERY POWERED COOLING UNIT**

(71) Applicant: **Jay Black**, Escondido, CA (US)

(72) Inventor: **Jay Black**, Escondido, CA (US)

(73) Assignee: **BIOFRIDGE INC.**, Escondido, CA (US)

(**) Term: **15 Years**

(21) Appl. No.: **29/696,953**

(22) Filed: **Jul. 2, 2019**

(57) **CLAIM**

The ornamental design for a heated lid for portable battery powered cooling unit, as shown and described.

DESCRIPTION

FIG. 1 is a top-front-left perspective view of a heated lid for portable battery powered cooling unit;

FIG. 2 is a front elevational view thereof;

FIG. 3 is a left side elevational view thereof;

FIG. 4 is a right side elevational view thereof;

FIG. 5 is a back elevational view thereof;

FIG. 6 is a bottom plan view thereof; and,

FIG. 7 is a top-front-left perspective view of the heated lid for portable battery powered cooling unit installed on a portable battery powered cooling unit.

The broken lines depict environment of the heated lid for portable battery powered cooling unit and form no part of the claimed design.

1 Claim, 4 Drawing Sheets
